UNITED STATES PATENT OFFICE.

ALPHONSE FERNANDEZ, OF WASHINGTON, DISTRICT OF COLUMBIA.

SUBMARINE VESSEL.

1,232,667.

Specification of Letters Patent. Patented July 10, 1917.

Application filed September 20, 1916. Serial No. 121,247.

To all whom it may concern:

Be it known that I, ALPHONSE FERNANDEZ, a subject of the King of Spain, residing at the city of Washington, in the District of Columbia, have invented certain new and useful Improvements in Submarine Vessels; and I do declare the following to be a full, clear, and exact description of the invention, such as will enable others skilled in the art to which it appertains to make and use the same.

The present invention has for its principal object to provide means for stabilizing and controlling the submerging of submarine vessels without the use of air pumps. To this end, I employ a plurality of compartments having vertically sliding power driven partitions for forcing water therefrom or drawing it into the same.

A further object of the invention is to construct the compartments and partitions in such a manner as to permit the upper portions of the former to serve as cargo or supply carrying chambers having said partitions as their bottoms.

Yet another object is to provide simple means for clamping the cargo against shifting.

Still further objects are to equip the water supply passage of the compartments with valves arranged on opposite sides of a central water inlet whereby water may be excluded from either end of the vessel and to devise means for preventing any objects or matter from entering the water inlet which might prevent closing of the cut off valve or valves with which the latter is equipped.

With the foregoing objects in view, the invention resides in certain novel features of construction and in unique combinations of parts to be hereinafter fully described and claimed, the descriptive matter being supplemented by the accompanying drawings which constitute a part of this application and in which:

Figure 1 is a central longitudinal section showing the general arrangement of parts, certain parts being omitted while others are shown out of their proper locations for the sake of clearness;

Fig. 2 is an enlarged longitudinal section of one of the compartments and a part of another, the use of one of the upper chambers for carrying liquid such as fuel being illustrated;

Fig. 3 is a view similar to Fig. 2, showing

the manner in which cargo may be clamped in place in the vertically moving partitions;

Fig. 4 is a horizontal section on the plane indicated by the line 4-4 of Fig. 3; 60

Fig. 5 is a vertical transverse section on the plane of the line 5-5 of Fig. 2; and

Fig. 6 is a detail horizontal section on the plane of the line 6-6 of Fig. 3.

In the drawings above briefly described, 65 the numeral 1 has reference to the hull or shell of the improved submersible vessel, 2 designates the engine, 3 the propeller, and 4 the vertical rudder. All of these parts are shown conventionally and may be of the 70 usual or any preferred construction.

A plurality of compartments C are spaced longitudinally of the vessel and are separated from each other by vertical partitions 5, each compartment C being divided into a 75 lower water chamber WC and an upper cargo or supply carrying chamber CC by means of a horizontal vertically movable partition 6. A pair of vertical screws 7 are disposed in each compartment C and are 80 threaded through the partitions 6 so that turning of said screws will raise or lower the partitions 6 as occasion may demand, for the purpose of taking water into or expelling it from the water chambers WC 85 without the use of pumps.

Any preferred means may be employed for driving the screws 7 but the upper ends thereof are preferably equipped with vertical shafts 8 whose upper ends are rotatably 90 mounted in a frame 9, each shaft 8 having a small gear 10 and a large gear 11 which mesh respectively with a large gear 12 and a small gear 13 loose on a vertical drive shaft 14 and capable of being locked thereto 95 by means of a clutch member 15 which may be shifted at will by the lever 16 and locked by the device 17. By this arrangement, when the gear 13 is locked to shaft 14, the two screws 7 will be rotated to move the 100 partition 6 downwardly at a rather slow rate of speed to expel the water from the water chamber WC, thus permitting the vessel to rise toward the surface of the water when a sufficient number of the chambers WC 105 have been totally or partially emptied. When the gear 12 is locked to shaft 14, however, and the direction of rotation of shaft 14 is reversed, the screws 7 will be swiftly turned in the direction for moving the partition 6 rapidly upward, thus permitting the chambers WC to be quickly filled with

water for submerging the vessel at short notice.

A water passage P extends longitudinally beneath the compartments C as shown in Figs. 2 and 5 and as shown most clearly in the last named view, said passage P is provided with a pair of opposed water inlets I which will be located at or near the center of the vessel. A valve 18 is provided in each inlet I for controlling the passage of water therethrough, these valves being shown as having vertical operating shafts 19 provided on their upper ends with operating levers 20 equipped with locking devices 21. For the purpose of preventing the entrance of any objects or matter such as mud, gravel or stones from the bed of a harbor or the like, into the inlets I and possibly preventing closing of the valves 18 at the proper time, screens or gratings 22 are located over or across the inlets I as depicted clearly in Fig. 5.

At times it becomes advantageous to exclude water from either end of the vessel and for this purpose valves 23 are disposed in the passage P on opposite sides of the inlets I, said valves having vertical operating shafts 24 equipped at their upper ends with operating levers 25 having locking devices 26.

Three-way valves 27 are provided at the lower ends of the partitions 5 for establishing communication between the passage P and the several water chambers WC. The valves 27 may be turned to the position shown at the right of Fig. 2 to establish communication with one chamber WC, may be reversed to place the adjacent water chamber in communication with the passage P, or as shown at the left of Fig. 2 said valves may be so turned as to establish communication between any two adjacent water compartments and at the same time place these compartments in communication with passage P. The valves 27 are provided with upright shafts 28 having hand wheels 29 on their upper ends, which wheels will be provided with suitable indicating means for disclosing the manner in which the valves 27 are set. It may here be explained that in addition to the positions above set forth, the valves 27 may be turned to a neutral position in which they obstruct communication between the passage P and water chambers WC between which they are located.

Gages 30 are employed for showing the height of the water levels in the numerous chambers WC, one gage being employed for each chamber. Any suitable means may be employed for operating the gages 30 but this is preferably done by connecting the interior mechanisms thereof to vertical rods 31 on the exterior of the compartments C, the lower ends of said rods being pivoted to 65 crank arms 32 on rock shafts 33 extending

through the sides of said compartments (see Figs. 2 and 5). Arms 34 are rigidly secured to the inner ends of the shafts 33 and are located in the chambers WC, each arm 34 having a float 35 to travel on the surface of 70 the water as shown in Fig. 2.

Other gages 36 are employed for the purpose of ascertaining the distances which the partitions 6 stand above their lowermost positions, one gage 36 being provided for each chamber WC. The gages 36 are connected to vertical operating rods 37 whose lower ends are pivoted to crank arms 38 on rock shafts 39 similar to 33. Crank arms 40 within the chambers WC are rigidly secured 80 to the inner ends of the shafts 39 and by means of links 41 are connected to the partitions 6. This operating means is preferable but others may well be employed.

To permit the expulsion of air from the 85 spaces between the water levels in chambers WC and the partitions 6, and for relieving suction which would be caused in the chambers WC by elevating of the partitions 6 above said water levels, air pipes 42 are employed, each of these pipes having a valve 43 by means of which the chambers WC may be placed in communication with a pipe line 44 which leads to an appropriate air tank not shown. The valves 43 are located at the 90 lower ends of the chambers WC and in order that they may be operated from the tops of the compartments C, they are preferably 95 equipped with chains 45 indicated in Fig. 5.

As above suggested, the chambers CC 100 may carry fuel or other liquids, whether they be cargo to be carried from one port to another or merely the supplies used on the trip. The liquid will be fed to the chambers in question and removed therefrom through pipes 46 which branch from a main pipe 47, each of said pipes 46 having a cut off valve 48. The pipe line 47 will supply fuel to the storage tank 49 for the engine 2 and a cut off valve 50 is interposed between said tank and the inlet or outlet 51 of said pipe line. Through pipe 51 the numerous chambers CC 110 may be filled or emptied as will be readily understood and this pipe may lead to suitable coupling means for connecting the submarine with a pipe lowered from a supply ship or permanently submerged at a wharf or the like. 51 may also be employed for filling the chambers CC when the vessel is 115 on the surface as will be readily understood. 120

In Fig. 1, the pipe line 47 is shown above the numerous compartments C for the sake of clearness and the branches 46 are depicted as if standing vertically. In reality, however, said branches 46 project horizontally 125 from one side of the chambers CC as shown in Fig. 5 and 46 extends alongside of said chambers. These parts, however, may be located at any other appropriate positions.

For determining the levels of the liquid 130

in the chambers CC, gages 52 are provided, said gages preferably having vertical operating rods 53 connected to crank arms 54 extending from rock shafts 55, the inner 5 ends of said rock shafts having rather long crank arms 56 carrying floats 57 on their free ends to ride on the surface of the liquid. Pipes 58 are clamped to the outer ends of the arms 56 and are connected by hoses or the 10 like 59 with the branch pipes 46 so that no matter whether the level of liquid lowers or rises, the same may be at all times removed from the chambers.

When solid cargo such as that shown in 15 Figs. 1 and 3 is to be carried in certain of the chambers CC, clamping frames 60 are employed for holding such cargo against shifting, said frames being of suitable construction and having split nuts 61 clamped 20 removably around the screws 7 by means of hand screws or the like 62 as shown clearly in Figs. 3 and 6. By this arrangement the frames 60 may rest upon the cargo and by means of the nuts 61 may be secured in 25 this position. As the partitions 6 are now raised and lowered the cargo and frames 60 will move therewith so that the former is at all times prevented from shifting, no matter to what extent said partitions are 30 adjusted.

Carrying of cargo or the like on the partitions 6 not only economizes in space within the vessel but the weight which is thus supported on said partitions assists materially in depressing them against the outside water pressure for the purpose of expelling water from the chambers WC, this being therefore considered a highly important feature of the invention.

40 In order that the gage 52 may indicate the amount which any partition laden with cargo may move upwardly, it is expedient to provide means for supporting the floats 57 upon the frames 60 when the latter are 45 in use. For this purpose, said floats are provided with rollers or other suitable shoes 63 to travel on tracks 64, one of these tracks being provided for each frame 60. The frames in question are cut away at one side 50 as shown in Fig. 4 so that they may clear the arms 56 and may be suspended at the top of the chambers CC when their use is unnecessary, and the tracks 64 are located normally in said cut away portions as like- 55 wise shown clearly in Fig. 4. In order that they may not shift the arms 56 upwardly when the frames 60 are suspended, the tracks 64 are retractable by any preferred means, being preferably provided with rigid 60 arms 65 sliding through guides 66 on the frames 60 and held against movement by hand screws 67.

When the frames 60 are not needed, any suitable means may be employed for holding 65 them at the upper ends of the chambers

CC, hooks 68 being shown in the present embodiment of the invention for this purpose (see Figs. 2 and 3). It is to be understood that when the frames 60 are to be raised, the split nuts 61 thereof are released 70 as evidenced by Fig. 2, and the tracks 64 are shifted inwardly so as to prevent the arms 56 and floats 57 from being supported thereby, thus allowing said floats to ride on the surface of the liquid in the chambers CC. 75

From the foregoing, it will be observed that I have devised a new type of submersible vessel which may or may not be armed, according to the type of work to be performed and the improved vessel may be put to any use to which it is applicable. In any case, however, it will be found to be highly efficient and reliable in operation, particular emphasis being laid upon the fact 80 that the water may be expelled from any of the chambers WC or taken into the same, or may be shifted from certain chambers to others without pumping air into said chambers as is now commonly done. This eliminates the use of air compressors for this purpose and the operation of the means for submerging and rising is therefore much more reliable, it being obvious that even should the mechanism for rotating the 85 screws 7 be damaged and thus out of running order, the shafts 14 may well be turned by hand since although the partitions 6 exert a tremendous pressure on the water in the chambers WC, provision of the screws 7 90 requires only that a small amount of power be used.

In submerging the vessel, it is necessary to take water into a suitable number of the water chambers WC and unless the partitions 6 of these chambers now stand at their lowermost positions, (see the left hand end of Fig. 1) they are moved to this position and during this operation all air from the water chambers is expelled through the pipes 42. This having been done, the valves 43 are closed and by means of the speed gearing 10—12, the partitions 6 of the chambers to be flooded are quickly raised, it being understood that the valves 18 and 23 are 105 now so set as to place passage P in free communication with the body of water in which the vessel is traveling. As the partitions 6 rise in this manner, water is drawn 110 into the chambers WC in sufficient quantity 115 to submerge the vessel. When the flow of water is to be checked, valves 18 are closed and the operating means of the partitions 6 are brought to a standstill. The gages 36 now show the distances which the afore- 120 said partitions stand above the bottoms of the water chambers WC while the float operated gages 30 indicate the number of gallons of water in the chambers WC. 125

When it is required to rise even slightly 130

toward the surface of the water, the partitions 6 of a suitable number of previously flooded chambers WC are started in a downward direction and this having been done, 5 the valves 18 are opened so that water is immediately expelled through the passages I with force. This will prevent the water under pressure on the exterior of the passage from having any tendency whatever to force 10 its way into the latter. When sufficient water has been expelled, the valves 18 are again closed simultaneously with stopping of the partitions 6.

When the stern of the vessel is to be lowered to permit the vessel to take an upward course through the water, the contents of say one of the front water chambers WC may be transferred to one of the rear chambers by respectively forcing the partitions 20 6 of these chambers downwardly and upwardly. Reversal of this operation will produce the opposite result as will be clearly understood. While transferring water from one end of the vessel to the other, any of 25 the valves 27 which are not necessarily used in this operation will preferably be closed to prevent the entrance of water into their respective chambers WC but if the partitions 6 of these chambers are in their lowermost positions or are already filled with water, closing of said valves is unnecessary.

All of the gages 30, 36 and 52 will preferably be located at the commander's quarters and each group of such gages will be so 35 located or identified in other ways as to permit it to be readily seen with which compartment C such group coöperates. It may here be explained that by simply reading the gage 52, the correct quantity of liquid 40 in any chamber CC can not be ascertained but it is necessary to read said gage in connection with the gage 36 of its particular group, comparing the indicating means of the two gages. This is due to the fact that 45 as the liquid in any chamber CC is raised with the partition 6 or lowered therewith, the float 57 will be correspondingly moved. This necessarily operates the gage 52 which by itself will thus indicate a greater or less 50 number of gallons when in reality the quantity remains the same.

As an example, when the partition 6 of any compartment C is at its lowermost position, gage 36 registers zero and with no 55 liquid supported on said partition, gage 52 also registers zero. Let us now assume that each foot in height of chamber CC has a capacity of one hundred gallons and that five hundred gallons of fluid are pumped 60 into said chamber. Gage 52 registers these five hundred gallons while gage 36 still stands at zero. If the partition 6 is now raised five feet, the indicator 36 will register this and the float 57 in moving upwardly five

feet will register one thousand gallons instead of five hundred, (one hundred additional gallons for each foot). From this, however, five hundred gallons (a hundred gallons for each foot which the partition was raised) is subtracted so that any one familiar with reading of the gages can ascertain that there are but five hundred gallons in the chamber CC rather than one thousand as would appear from reading gage 52 alone.

From the foregoing, the general construction, manner of operation and advantages of the improved vessel will be readily understood by those skilled in the art and it will also be clear that for the sake of illustration, a number of devices which must necessarily be used on all submarines are not shown or described. I wish it also understood that although the drawings disclose certain specific details of construction for illustrative purposes, and such details are here described, I do not wish to be limited thereto, otherwise than to the extent claimed.

I claim:

1. A submersible vessel having a plurality of longitudinally spaced submerging chambers, a water passage extending longitudinally of the vessel and having a water inlet at or near the center of the latter, valve means for closing said inlet, and additional valve means for closing said passage on either side of said inlet to exclude water from either end of the ship.

2. A submersible vessel having one or more compartments each divided by a vertically movable power driven partition into a lower water chamber and an upper cargo or supply carrying chamber and an entrance into said upper chamber.

3. A submersible vessel having one or more compartments each divided by a vertically movable power driven partition into a lower water chamber and an upper cargo or supply carrying chamber, and a frame in each or any upper chamber for clamping cargo therein against shifting.

4. A submersible vessel having one or more compartments each divided by a vertically movable power driven partition into a lower water chamber and an upper cargo or supply carrying chamber, a frame in each or any upper chamber for clamping the cargo against shifting, and means for supporting said frame at the top of its respective chamber when oil or the like is to be carried therein.

5. A submersible vessel having one or more compartments each divided by a vertically movable partition into a lower water chamber and an upper cargo or supply carrying chamber, one or more vertical screws passing through the partition for shifting the same vertically, a cargo clamping frame in each or any upper chamber, and means

on said frame engaging the screw or screws whereby to adjust the partition and frame simultaneously.

6. A submersible vessel having one or 5 more compartments each divided by a vertically movable partition into a lower water chamber and an upper cargo or supply carrying chamber, one or more vertical screws passing through the partition for shifting 10 the same vertically, a cargo clamping frame in each or any upper chamber, and a split nut or nuts on said frame engaging the screw or screws whereby to simultaneously adjust the partition and frame and to permit 15 the latter to be shifted independently of the former.

7. A submersible vessel having one or 20 more compartments each divided by a vertically movable partition into a lower water chamber and an upper cargo or liquid carrying chamber, a cargo clamping frame in each or any upper chamber, means for supporting said frame at the top of said chamber, a gage for indicating the height of liquid 25 in the upper chamber, said gage including a float to ride on the surface of the liquid, and means carried by the aforesaid frame for supporting said float when said frame is in operation.

30 8. A submersible vessel having one or more compartments divided by a vertically movable partition into a lower water chamber and an upper cargo or liquid carrying chamber, a cargo clamping frame in each 35 or any upper chamber, means for supporting said frame at the top of said chamber,

a gage for indicating the height of liquid in the upper chamber, said gage including a float to ride on the surface of the liquid, a shoe carried by the float, and a retractile track carried by the frame to support said shoe slidably thereon when said frame is in use.

40 9. A submersible vessel having a plurality of longitudinally spaced water chambers, 45 a common passage for supplying water to any or all of said chambers, sliding partitions in said chambers having operating shafts, and means operatively associated with said shafts for so operating them as 50 to shift the partitions to expel water from or draw it into the chambers.

10. A submersible vessel having a plurality of transverse partitions dividing it into a number of water chambers, a common 55 passage extending beneath the several chambers for supplying water to any or all thereof, two-way valves at the lower ends of said partitions for admitting water from the common passage into either or both of the 60 chambers on opposite sides of said partitions, and sliding power driven partitions in the chambers for drawing water into or forcing it from said chambers.

65 In testimony whereof I have hereunto set my hand in the presence of two subscribing witnesses.

ALPHONSE FERNANDEZ.
